METHOD OF AND APPARATUS FOR MAKING
BAGS AND THE LIKEAdolph Potdevin, Garden City, N. Y., assignor
to Potdevin Machine Company, Brooklyn,
N. Y., a corporation of New York

Application October 10, 1934, Serial No. 747,681

14 Claims. (Cl. 93—8)

This invention relates to the making of bags and particularly to the making of bags from materials such as cellulose acetate, cellulose hydrate, glassine, or other materials or any combination of two of these materials, to obtain pleasing effects and attractive packages, combined with an efficient and economical method of making the same.

The invention provides for the making of the bag from two webs of material brought together in superimposed relation, the opposite edges of one web being folded over the edges of the other web and pasted or otherwise secured thereto.

In the drawing accompanying this application:

Fig. 1 is a plan view diagrammatically illustrating the various stages in the handling of the web;

Fig. 2 is a plan view of the first step of bottoming the bag;

Fig. 3 is a plan view of a finished bag;

Fig. 4 is a sectional view on the line 4—4 of Fig. 3;

Fig. 5 is a sectional view on the line 5—5 of Fig. 3;

Fig. 6 is a sectional view of a modified form of bag; and

Fig. 7 diagrammatically illustrates the machine for the making of the bag.

Referring to the drawing in detail, the materials for making the bag are taken from two supply rolls 1 and 2. The web of material from the roll 1 is designated 3, and as it leaves the supply roll 1, traveling in the direction of the arrow thereon, it passes around idler roller 4 and then through the edge folding mechanism 5 by which the opposite edges of the web are turned inwardly as shown at 6 to crease the web adjacent its edges, as shown at 6' in Fig. 1. The web next passes between rollers 7 where the edges of the web are spread outwardly again, so that the web is again in a flat condition, and between two cutters 8 on opposite sides of the machine which cut a section out of one side of the web, the cutout being shown in Fig. 1 at 9 and 10, for instance.

The cutters 8 are rotatable about axes parallel to the travel of the web.

The web continues to advance between rollers 11 and 12 and about a roller 13 which is located adjacent the gluing mechanism. This gluing mechanism is diagrammatically illustrated, and comprises glue pot 14, glue roller 15 and glue applying roller 16, the latter being adapted to apply glue, paste or other suitable adhesive along

the edges of the paper as shown at 17 and 18, so that when the opposite edges 6 of the web are again folded over along the creases 6' the glue or other adhesive will be on the underside thereof. The gluing roller 16 is also adapted to apply adhesive 19 transversely of the paper as seen in Fig. 1.

The web 21 from the supply roll 2 is slightly narrower than the web 3 and passes between forwarding rollers 22 past cut off mechanism 10 23 by which it is cut off into sections 21', and through a series of forwarding rollers 24 to superimposed position with respect to the web 3 between roller 13 and the brush roller 20. The peripheral speed of the forwarding rollers 24 is 15 the same as the linear speed of the web 3, the web sections 21' are deposited in spaced relation upon the web 3 between consecutive sets of notches 9 and 10. The speed of the feed rollers 22 can be varied relatively to the operation of cut-off mechanism 23 to vary the length of the web sections 21'.

The roller 20, as will be understood, is the width of the web 21 or, in any event, narrower than the distance between the strips of adhesive 17 and 18 and is for wiping the web sections 21' upon web 3 so as to insure the two being attached to each other by the adhesive 19. In practice this mechanism is all properly timed so that the cut-off mechanism 23 will cut the web 21 into 20 proper lengths depending, of course, upon the length of the bag being made.

As the web sections 21' and web 3 in superimposed relation pass between the rollers 13 and 20 the edges of the web 3 will be engaged by 35 edge-folding mechanism, diagrammatically illustrated at 25, which is adapted again to fold the opposite edges 6 of the web 3 along the creases 6' over upon the web sections 21', as shown at 26 in Fig. 1. Inasmuch as these edges have already had adhesive applied thereto it will be apparent that the web sections 21' and the web 3 now will be attached to each other in superimposed relation with the edges of the web 3 turned over and enveloping the edges of the web 45 sections 21'.

The material continues its forward advance to and between a pair of rollers 27 and a pair of rollers 28 to cut-off mechanism 29 where the web 3 is severed transversely midway of the 50 notches 9 and 10 into bag lengths provided with end flaps 32 and 33 in the lower wall of the assembly, as viewed in Fig. 1, the web being held taut during the cutting off or severing operation by rollers 30.

The partially completed bag designated 31 in Fig. 1 next is advanced to between upper roller 35 and lower roller 36. The roller 35 rotates in the direction of the arrow thereon and is provided on its periphery with a creaser blade 37 cooperating with an abutment 38 on the lower roller 36. As a bag length comes up to these two rollers 35 and 36 the blade 37 on the roller 35 engages the bag length along the line 39 of Fig. 2 forcing the material below the plane of its travel at which time a squeezing clamp 40 on the roller 36 engages this depressed portion of the traveling material and squeezes the same against the abutment 38 so as to insure thorough creasing along the line 39 of Fig. 2. The clamp 40 is controlled by a stationary cam 41.

As the blade 37 finishes its function the gluing blade 42 which is carried on the periphery of the roller 35 and which picks up adhesive from roller 43 engages the upper face of the bag length 31 back of the crease 39 to apply adhesive across the face of the member 31, as shown at 44 in Fig. 2. The creasing of the leading end of the length 31 by the members 37 and 38 will cause the leading end of the bag length 31 to stand upwardly at an angle to the plane of the bag length so that when this end of the bag length passes the roller 45 the flap 33 and a short length of the leading end of the web section 21' will be folded over, as illustrated in Fig. 3, to bring the underside of the flap 33 upon the adhesive 44 thereby to bottom the bag. The bottomed bag then passes between a pair of rollers 46 and 47 which may be resiliently mounted, one of these rollers carrying a pressure bar 48 adapted to engage the upper surface of the bag above the adhesive stripe 44 to insure thorough adherence of the turned over flap 33 to the upper face of the web section 21'. As the trailing end of the bag length passes the rollers 35, 36 it is engaged by a creaser blade 49 on the periphery of the roller 35 which cooperates with a creaser blade 50 on the periphery of the lower roller 36, causing the bag length to be creased on its trailing end, as shown at 51 in Fig. 3, to crease the bag transversely at the edge of the trailing end of the web section 21', to facilitate closing the flap 32 when the bag is in use.

The bag illustrated in Fig. 6 is made in the same way as the bag of Fig. 4, except that the leading end of the web section 21' is turned over slightly as shown at 52 in Fig. 4, whereas in Fig. 6 the end is not turned over in the bottoming operation.

It is to be understood that changes may be made in the details of construction and arrangement of parts above described within the spirit and scope of my invention.

What I claim is:—

1. In apparatus of the class described, the combination of feed rollers for continuously advancing a flexible web or strip, feed rollers for continuously advancing sections of a second and narrower flexible web or strip in superimposed relation with respect to the first web or strip, one of said strips eventually constituting the front wall of the bag and the other of said strips constituting the rear wall, means for applying adhesive adjacent the edges of the wider web or strip, folding mechanism for folding the pasted edges of the wider strip over and upon the superimposed sections of the narrower strip to secure the same thereto.

2. In apparatus of the class described, the combination of feed rollers for continuously advancing a flexible web or strip, feed rollers for

continuously advancing sections of a second and narrower flexible web or strip in superimposed relation with respect to the first web or strip, means for applying adhesive adjacent the edges of one of said webs or strips, folding mechanism for folding the edges of the wider strip over and upon the superimposed sections of the narrower strip, so as to secure the two strips to each other, and severing means for severing the strip thus formed into bag lengths. 10

3. In apparatus of the class described, the combination of means for continuously advancing a flexible web or strip, paste-applying means for applying adhesive transversely of said strip, means for advancing a second and narrower flexible web or strip, severing mechanism for severing said narrower web into sections, means for advancing said sections in spaced relation into superimposed relation with respect to said wider strip, paste-applying means for applying stripes 20 of adhesive along the edges of one of said strips, means for imposing pressure upon the superimposed web section toward the said transversely pasted portion of the wider web or strip, a folding device for folding the edges of the wider strip over and upon the narrower web sections to secure the same thereto, and severing mechanism for severing the strip thus formed into bag lengths. 25

4. In apparatus of the class described, the combination of means for continuously advancing a flexible web or strip, paste-applying means for applying stripes of adhesive along the edges of one of said strips, severing mechanism for severing said narrower web into sections in spaced relation, means for advancing said sections into superimposed relation with respect to said wider strip, means for imposing pressure upon the superimposed web section toward the said transversely pasted portion of the wider web or strip, a folding device for folding the edges of the wider strip over and upon the narrower web sections 45 to secure the same thereto and form a single walled tube, and severing mechanism for severing the tube thus formed into bag lengths. 50

5. In apparatus of the class described, the combination of means for advancing a flexible web or strip, notching means for providing notches in said web, paste-applying means for applying stripes of adhesive along the opposite edges of said strip, means for advancing a second and narrower web, severing mechanism for severing the narrower web into sections, forwarding means for forwarding said web sections in superimposed relation with respect to the first mentioned web between consecutive sets of notches, a folding device for folding the pasted edges of the wider web over and upon the superimposed narrower web sections, and severing mechanism for severing the wider web transversely into bag lengths intermediate the ends of said notches. 60

6. In apparatus of the class described, the combination of means for advancing a flexible web or strip, notching means for providing notches in said web, paste-applying means for applying paste to the surface of said strip transversely thereof and for applying stripes of adhesive along the opposite edges of said strip, means for advancing a second and narrower web, severing mechanism for severing the narrower web into sections, forwarding means for forwarding said web sections in superimposed relation with re- 75

5 spect to the first mentioned web between consecutive sets of notches, a folding device for folding the pasted edges of the wider web over and upon the superimposed narrower web sections, and severing mechanism for severing the wider web transversely into bag lengths intermediate the ends of said notches.

10 7. In apparatus of the class described, the combination of feeding mechanism for continuously advancing a web of bag material, mechanism for depositing and adhesively fastening strips of narrower material upon the said web in longitudinally spaced relation, pasting and folding mechanism for pasting the edges of the wider web and folding them over upon the face of the narrower strip, severing mechanism for severing the wider web transversely between adjacent narrower strips to provide bag lengths with a projecting flap at each end, creasing mechanism for creasing the leading end of the bag length to the rear of the flap at that end of the bag length, paste applying mechanism for applying paste to the face of the bag length to the rear of said crease, means for folding the flap at the leading end of the bag length over upon said pasted area to bottom the bag, and creasing means for creasing the trailing end of the bag length at the base of the flap at that end of the bag length.

15 8. In the making of bags and the like, the method which comprises continuously advancing a web of bag material, imposing strips of narrower bag material in spaced relation upon the first mentioned web, applying paste to the edges of one of said strips, and folding the edges of the first mentioned web over and upon the said strips to secure the edges of both strips to each other and form a single walled tube of bag material.

20 9. In the making of bags and the like, the method which comprises notching the edges of an advancing web of bag material, applying paste to the body of the web and to the edges of the web, imposing strips of narrower bag material upon said web between said notches to be attached thereto by the first mentioned paste, folding the pasted edges of the wider web over upon the said strips, severing the said web intermediate the adjacent ends of said strips to provide bag lengths with a projecting flap at each end, and finally folding the flap at one end of the bag length over upon the adjacent end of the strip and pasting it down to bottom the bag.

25 10. In the making of bags and the like, the method which comprises notching the edges of an advancing web of bag material, applying paste to the unnotched edges of the web, between the notches imposing strips of narrower bag material upon said web at each side of said notches, and securing the leading edge of the narrower strips to the web, folding the pasted edges of the wider web over upon the said strips, severing the said web intermediate the adjacent ends of said strips to provide bag lengths with a projecting flap at each end, advancing the bag lengths, and

30 on their advance applying paste to the superimposed strip adjacent the leading end thereof, creasing the bag length adjacent the base of the flap at the leading end of the bag length, folding this flap along the crease over upon the pasted area of the superimposed strip to bottom the bag, and finally creasing the bag length adjacent the base of the flap at the trailing end of the bag length.

35 11. The method which comprises folding over the side edges of a strip of bag material, unfolding said edges, notching said unfolded edges at predetermined intervals, applying adhesive to said unfolded edges as well as transversely of the strip, severing an advancing strip of narrower material into sections at regular predetermined intervals, feeding said severed strip sections in superimposed relation to the wider strip and adhesively fastening the leading end of the narrower strip sections to the wider strip at regular intervals between the notches of the wider strip by said transverse adhesive.

40 12. The method which comprises folding the pasted edges of a web of bag material over the edges of narrower and shorter strips disposed thereon in spaced relation, severing the wider and longer web into bag lengths between the equally disposed narrower strips and folding the leading end of the wider web including the leading edge of the narrow strip edges adhesively secured thereto against the pasted face of the narrow strip section to form the bottom of the bag.

45 13. In the making of bags and the like, the method which comprises notching the edges of an advancing web of bag material, applying paste to the unnotched web, imposing spaced strips of narrower bag material upon said web at each side of the notches, and securing the leading end of the narrower strips to the web, folding the pasted edges of the wider strip over upon said strips, severing the said web between said strips, to provide a flap at one end, advancing the bag lengths, and on their advance applying paste to the superimposed strip adjacent one end thereof, creasing the bag length adjacent the pasted end, folding this end of the bag length along the crease over upon the pasted area of the superimposed strip to bottom the bag and finally creasing the bag length adjacent the base of the flap at the other end of the bag length.

50 14. In the making of bags and the like, the method which comprises advancing bag material in the web, imposing strips of narrower material in spaced relation upon the first mentioned web, applying paste transversely to the face of one of said materials before the two are superimposed, applying paste to the edges of one of said materials, and folding the edges of the web over and upon the said narrower strips to secure the edges of the two materials to each other to form a single walled tube.

55 60 ADOLPH POTDEVIN.
